UNITED STATES PATENT OFFICE.

CHARLES L. STURTEVANT, OF WASHINGTON, DISTRICT OF COLUMBIA, ANCILLARY ADMINISTRATOR OF SAMUEL LOWE, DECEASED, ASSIGNOR TO JOHN WILLIAM LAMB AND JESSE HIND, OF NOTTINGHAM, ENGLAND, EXECUTORS OF SAID LOWE.

KNITTING-MACHINE.

SPECIFICATION forming part of Letters Patent No. 621,723, dated March 21, 1899.

Application filed December 13, 1897. Serial No. 661,766. (No model.)

To all whom it may concern:

Be it known that SAMUEL LOWE, of Nottingham, in the county of Nottingham, England, now deceased, did invent certain new and useful Improvements in Knitting-Machines for Tubular Fabrics, of which the following is a specification.

The object of this invention is to produce on straight-bar bearded-needle knitting-machines fashioned tubular work—such as stockings, socks, vest and shirt sleeves, pant-legs, and the like—and also fashioned tubular work with a selvaged opening or division, as when making pants in halves and also complete pairs of pants without seams.

The machine selected to illustrate this invention is of the well-known straight-bar bearded-needle rib-frame type, in which two sets of needles carried by straight bars are arranged to cross each other substantially at right angles, those of one set working between those of the other set, as shown in many patents—for example, in United States Patent No. 28,133, dated May 1, 1860—and the mechanism necessary for carrying out this invention is described with reference to such machine, there being such differences with respect to timing and arrangement as will be readily understood by the knitting-machine builder after the action of the knitting devices have been hereinafter fully explained. It will be therefore unnecessary to refer the several movements of the knitting instruments to their original source or to illustrate the construction of the machine further than to show the shape of the cams for operating the needle-bars and the mechanism adopted for "knocking over" the courses according to the present invention.

In the accompanying drawings, Figure 1 is a vertical cross-section of a bearded-needle rib-frame, showing the improvements which constitute the present invention for producing fashioned tubular work, such as the legs of stockings, and Fig. 2 shows in plan view and on an enlarged scale so much of one division of a rib-frame as will illustrate the position of the fashioning mechanism required

for producing a fashioned tube. Fig. 3 shows, detached, in front elevation the fashioning-point holder. Fig. 4 shows in side elevation so much of the mechanism as serves to operate the horizontal needles, their position in the machine being indicated by their relation to the fixed presser-bar. Fig. 5 is a side elevation of the mechanism for moving the knocking-over bar of the vertical needles. Fig. 6 shows in side elevation so much of the mechanism as serves to operate the knocking-over slide for the horizontal needles. Fig. 7 shows in side elevation the mechanism for imparting an independent rocking motion to the fashioning-points used in conjunction with the horizontal needles. Fig. 8 is a front elevation of so much of one division of the machine as will serve to illustrate a suitable arrangement of mechanism for operating the thread-carriers and shogging the cam-shaft, and Fig. 9 is a detached view of the mechanism used for arresting the movement of the thread-carriers and shogging the cam-shaft.

Diagrams 1 to 11, inclusive, illustrate the cycle of movements of the knitting devices to produce tubular work.

It is for the purpose of simplifying the description that reference in this part of the specification is made only to the formation of the seamless tubular part of the stocking in the working of the machine, the mode of producing the foot in conjunction with the fashioned tube being well understood by the experienced knitter.

Referring now to Fig. 1, A is the cam-shaft, which is rotated, as heretofore, through a spur-wheel *a*, gearing into a spur-pinion on the main driving-shaft. (Not shown in the drawings.) From this cam-shaft all the movements are derived that it will be necessary hereinafter to refer to.

Upon the shaft A the various cams for operating the vertical and horizontal needles during the knitting and fashioning are situate.

1 1* represent the cams which operate the needle-bar B, which carries the vertical needles *b*, and 2 2* represent the cams which op-

erate the needle-bar C, which carries the horizontal needles c. The sinkers d, which indent the thread, slide, as usual, in the sinker-bar D, which constitutes also the presser-bar 5 for both sets of needles, its vertical edge d' serving to press the beards of the needles b and its under face d² forming the presser for the beards of the needles c.

The vertical needles b are mounted in their 10 needle-bar B, as usual, which bar is pivoted to arms b', projecting from a rock-shaft B'. This shaft is rocked through the cam 1, which actuates an arm b², pendent from the rock-shaft, and thus the vertical movement of the 15 needles b is obtained. Extending down from the needle-bar is an arm b³, which is pivoted to a link b⁴, connecting with an arm b⁵, pendent from a rock-shaft B² and carrying at its lower end a bowl which bears upon the cam 20 1*. As these cams rotate together a compound vertical and rocking motion will be imparted to the vertical needles, as heretofore.

The horizontal needles c are secured to their 25 bar C, as usual. This bar C is pivoted to the arm c' of a rock-shaft C', actuated from a cam 2 (see Fig. 4) on the cam-shaft A. Bearing on this cam 2 is a bowl of an arm c², fixed to and pendent from the rock-shaft C', which as it rocks under the rotation of the cam 30 imparts the to-and-fro motion to the horizontal needles. These needles are also simultaneously rocked by the cam 2*, a bowl bearing on which and carried by a pendent arm c³ on a rock-shaft C² transmits through an 35 arm c⁴ and a link c⁵ the requisite rocking motion to the bar C of the horizontal needles c.

The knocking-over bar E, which carries the 40 bits e for casting off the formed loops from the vertical needles b, is carried similarly to the needle-bar B. It is pivoted to an arm e', secured to a rock-shaft E', pendent from and secured to which is an arm e², carrying a bowl which bears on the cam 3 (see Fig. 5) of the cam-shaft A. The rotation of this cam lowers 45 the knocking-over bits, so that the horizontal needles c may be brought into contact with the pressing-surface d² of the sinker-bar D. The bar E is also connected to arms e³, which are pivoted at e⁴ to levers e⁵, and these latter 50 are jointed to arms e⁶, which are loosely mounted on the shaft B² and fitted with bowls which are held in contact with cams or disks on the shaft A by means of springs for the purpose of maintaining the verticality of the 55 knocking-over bar.

For effecting the knocking over of the work 60 formed on the needles c the knocking-over slide F is provided. This slide, which is carried by the needle-bar C and rocks therewith, has a bracket extension f (see Fig. 6) on its under side, the extremity of which takes into the forked ends of a lever f', secured to a rock-shaft F'. Pendent from this rock-shaft is an arm f², fitted with a bowl which bears on a 65 cam 4 on the cam-shaft A. The forward edge of the slide F is notched to receive the ends of the needles c and allows of the slide enter-

ing between the needles, so as to knock over the last-formed row of loops. The cam 4 is so timed as to insure the advance of the slide 70 when the knitted loops are on the beards of the needles and are ready to be knocked over or cast off.

G is the thread-carrier, mounted on the sliding rod G' and actuated by the usual slur-box, 75 but in this case timed to lay its thread twice upon the stems of the vertical needles during one rotation of the cam-shaft A by means of the mechanism shown at Figs. 8 and 9 and hereinafter particularly described with relation to 80 the manufacture of paints. The action of the thread-carrier, it will be understood, is suspended during fashioning, as usual, its arrest on the right-hand side of the division being effected immediately before the cam-shaft is 85 shogged to bring the narrowing-cams into action.

H is the holder for the fashioning pins or points. It is carried, as usual, by a rack-bar H', (see Figs. 2 and 3,) which is free to rise 90 and lift the points out of action. These points are shown as situated at the left-hand side of the division only and will suffice when tubular - fashioned work is being made. The thread-carrier when arrested to allow of the 95 fashioning mechanism being brought into action is at the right-hand side of the division; but as these fashioning-points work in precisely the same way as those of other knitting-machines (but in this particular machine 100 at one side only of the division) no detailed description, either of their action or of the means for setting them in action, will be required further than this, namely: There are two sets of fashioning-points h and h* carried by the holder H. The points h are firmly fixed to the holder and are slightly curved to insure proper contact with the vertical needles for the purpose of taking off the loops and moving them to the adjacent needles. 110 The bent pins or points h* are set in the end of a rock-lever h', pivoted to the holder H and capable of receiving an independent rocking motion. These points act on the horizontal selvage-needles and are used for transferring the loops on the same to adjacent needles. 115 The top of this rock-lever h' is forked to enable it to receive a rocking motion without interfering with the rising-and-falling motion, which motion is common to both sets 120 of points and is derived from cams in the manner well understood.

The independent motion of the points h* (see Fig. 7) is derived from the cam 5 on the cam-shaft A. Bearing upon this cam is a 125 bowl carried by a rock-lever h², fulcrumed at H². A link h³, pivoted to this rock-lever, connects at its upper end with a crank-lever h⁴, fulcrumed at H³ and carrying at its upper end a link h⁵, which is pivoted to a crank-lever h⁶, fulcrumed at H⁴. The lower end of this crank-lever is connected to a horizontal rod h⁷, which extends from end to end of the machine and engages with the forked ex-

tremity of the rock-levers h' of each division. As therefore the cam-shaft rotates, and thereby causes the fashioning-cams (not shown in the drawings) to bring down the narrowing-points h and h^* , the cam 5 will advance the points h^* , cause them to take up the formed loops on the end needles c of the division, replace the loops on adjacent needles, and retire, preparatory to the rising of the fashioning-points, clear of the knitting mechanism.

It should be remarked that in order to insure the placing of the indented thread upon the stems of the horizontal needles and to secure a perfect union between the ends of the two courses of knitting on the vertical and horizontal needles, respectively, the vertical needles overlap the horizontal needles, as in bearded-needle rib-frames and as indicated in Fig. 2.

In order to make more clear the combined action of the parts above described, a series of diagrams is appended to the drawings, which will show the progressive action of the knitting instruments during one rotation of the cam-shaft, in which time a complete course is formed on each row of needles, and such courses are joined at the end needles and form tubular work.

Referring to Diagram 1, the vertical needles b are at their highest position and the thread-carrier G has passed from left to right, laying the thread on their stems, and the sinkers d have indented and divided the thread, as usual. At this stage the horizontal needles c are inactive. Diagram 2 shows the needles b pressed and the formed loops landed onto their beards. Diagram 3 shows a further descent of the needles b , the knocking-over bits e having come into action and cast off the formed loops. Up to this point the vertical needles have operated to form a course, as in ordinary machines. The next step in the cycle is to employ the needles b for receiving the thread for the horizontal needles c . To this end they rise to the position of Diagram 4, when the thread-carrier is moved from right to left, laying, as before, a thread upon their stems, which thread is indented by the sinkers d , as in Diagram 1. The horizontal needles c , hitherto quiescent, have now commenced to move in order to receive the indented thread from the needles b . Diagram 5 shows the needles b in the position for laying the thread upon the needles c , the knocking-over bits e having been lowered to allow of the needles c being moved under the presser d^2 to receive the thread from the vertical needles. The rocking of the needles b next brings the indented thread under the beards of the needles c , which are now rocked to press those needles into contact with the pressing-surface d^2 and close their beards upon the indented thread, as indicated by Diagram 6. The formed loops on the stems of the needles c are next, while the beards of those needles are pressed, landed on the beards. For this purpose the needles c move back to the position

of Diagram 7 through the knocking-over slide F . In order to free the vertical needles from the indented thread just laid on the horizontal needles and at present held in the beards of the vertical needles, these latter ascend and move forward to be pressed, as seen at Diagram 8. Meanwhile the needles c are rocked upward to land the indented thread in contact with the vertical needle-stems onto the beards of those needles, as shown at Diagram 9. The needles b now descending free themselves from the indented thread, as shown at Diagram 10. The knocking-over slide, which coacts with the horizontal needles c , then moves forward beyond the heads of the needles and knocks over the formed loops of the needles c , as shown at Diagram 11. At the same time the knocking-over bits e commence to rise for the purpose of assuming their active position, as in Diagram 1. This completes the cycle of motions of the knitting instruments, which motions are recommenced by the rising of the needles b to the position shown in Diagram 1.

So long as the cycle of movements is repeated tubular work of a given uniform diameter will be produced, and when it is required to fashion the fabric the traverse of the thread-carrier is arrested and the cam-shaft shogged to bring the fashioning-cams and the mechanism connected therewith into action. The knitting being now resumed, the work will be from time to time automatically interrupted and fashionings made according to the requirements of the article or fabric being manufactured.

The above description explains the method of making tubular-fashioned work; but when it is desired to form a selvaged opening or division in the work—as, for example, when the work known as “half-pants” is to be produced—the leg is made by the method described, and on the completion of the same instead of forming one course on each set of needles alternately two courses in succession are produced on each set of needles alternately, and this, with the requisite fashioning, is continued until the body of the pant is completed. Back and front selvages are thus formed, the former to be united with the back selvage of a corresponding half-pant and the other selvage to receive the strip forming part of the buttonhole attachment. As an illustration of this mode of working let it be supposed that a course has been completed on the horizontal needles and the thread-carrier is at the right-hand side of the needles. The carrier now moves to the left and a course is knitted on the vertical needles, which course may be considered as a continuation of the last course knitted on the horizontal needles. The carrier next moves to the right and a second course is knitted on the vertical needles. The carrier then returns to the left and a course is knitted on the horizontal needles, this course being a continuation of the last course knitted on the

vertical needles. The carrier again returns to the right and a second course is knitted on the horizontal needles. Thus the selvaged opening is formed on the left-hand side of the 5 division. In producing this work it will be understood that the thread-carrier delivers its thread at every traverse onto the stems of one and the same set of needles.

For enabling the selvaged opening in the 10 work to be made the machine is provided with duplicate cams and the cam-shaft is moved endwise at the required time or the cam-bowls are moved from one set of cams to the other. Thus the machine may be fitted 15 with three sets of cams, the first set producing one course on each set of needles alternately for one revolution of the cam-shaft. The second set of cams may produce two courses in succession on the vertical needles at each 20 revolution of the cam-shaft, and the third set of cams would produce two courses in succession on the horizontal needles at each revolution of the cam-shaft.

The cam-shaft or the cam-bowls will be 25 moved as required by any arrangement of mechanism similar to that generally used for similar purposes in existing machines.

In knitting half-pants it will be found 30 desirable to fashion on one selvage only—namely, the back selvage. In this case the fashioning-points for one set of needles only will be brought into use.

For making a complete pair of pants without seams the tubular body extending to the 35 fork of the pants is made by the aid of a single thread-carrier. When this point is reached, an additional thread-carrier is thrown into action and the traverse of both carriers is limited to the size of the leg and to the fashionings in the same, the machine thus producing two tubes at the same time. In this way the tubes forming the legs are united to a single tube forming the body of the pants. Pants of this description may also be made 40 by starting at the ankle of both legs with two carriers, completing the legs up to the fork, and then making the body with the aid of one carrier only. In effecting this work it will be understood that the fashioning will proceed 45 at both sides of the division. The machine must therefore be fitted, like the ordinary fashioning-machines, with a double set of fashioning-points for each division.

The mechanism for throwing the thread-carriers in and out of action may be of any 50 approved construction, but that shown at Figs. 8 and 9 is the arrangement preferred for giving two traversing motions of the thread-carriers for one rotation of the cam-shaft A. Mounted loosely on this shaft is a 55 miter-wheel a' , the boss of which carries a collar a^2 , which is notched to receive a projection a^3 from the sliding clutch a^4 , actuated by a forked arm I. This fork enters an annular groove in the clutch a^4 and is loosely mounted upon the shogging-shaft I' between fixed collars, which impart to it the requisite

lateral shifting motion in the manner hereinafter described. A lug projecting from the forked arm interlocks with the teeth of the 70 miter-wheel a' when the sliding clutch is disengaged, and thus retains the miter-wheel in position for the clutch to reengage therewith. In order to prevent this miter-wheel from moving endwise when the sliding clutch is 75 thrown out of action, and thereby disengaging itself from the miter-wheel g , which it is intended to drive, a finger projecting from the framing enters a groove on the boss of the miter-wheel a' on the inner side, and thus 80 retains it in gear with the miter-wheel g . This wheel is keyed to a transverse shaft g' , which has its bearing on the framing of the machine and carries at its rear end a snail-cam g^2 . This cam acts alternately on the 85 bowls g^3 g^3 , mounted on studs carried by a sliding bar g^4 , which is connected by a link g^5 to a vertical oscillating arm g^6 , having its fulcrum at the base of the machine. The upper end of this arm is connected, as shown 90 in Fig. 8, by a link-rod g^7 to the ordinary slur-box G^2 , in which are grooves in which the thread-carrier rods $G' G'$ rest and from which the sliding motions of said rods are obtained by frictional contact with the slur-box. This 95 friction driving device for the thread-carrier rods is well known in the trade and is illustrated in United States Patent No. 349,352, dated September 21, 1886. As the cam-shaft A is rotated its motion will be transmitted 100 through the miter-wheels $a' g$ to the cam g^2 , which for every rotation imparted to it will (by striking the studs g^3 g^3 alternately) give two vibrations to the oscillating arm g^6 and by reason of the connection of this arm with the 105 slur-box G^2 two traverse motions will be given to the slur-box, and consequently two lays of thread will be delivered to the needles for every rotation of the cam-shaft. The mechanism for initiating these movements is shown 110 at Fig. 9, where I^2 is an arm pendent from a fixed point and carrying a bowl i , which bears upon a cam 6 on the cam-shaft A. Mounted loosely on the axis of the bowl is a pawl i' , 115 which takes into the teeth of a ratchet-wheel i^2 , loose upon a stud-axle, which is made fast to the framing. This ratchet-wheel carries a cam i^3 , upon which bears a stud i^4 , carried by an arm i^5 , made fast to the shogging-shaft I'. As, therefore, this cam is rotated it will 120 rock the shogging-shaft I', giving it two movements for each rotation of the cam. This movement of the shogging-shaft serves, through the action of the ordinary shogging-cam I^3 I^4 on the cam-shaft A, to shift the 125 forked arm I, which it carries, and disengage the clutch a^4 from the boss of the miter-wheel, and thereby arrest the thread-carrier. A further result which it attains is to impart an endwise motion to the rotating cam-shaft 130 A, and thereby to bring into action the fashioning-cams. It is, however, necessary to provide a variable speed of rotation of the cam i^3 in relation to the rotation of the cam-

shaft in order that the requisite variations in the number of uninterrupted courses of knitting may be secured. This end is effected by changing the ratchet-wheel for one of a greater or less number of teeth to suit the work in hand.

Referring now to Fig. 8, it will be seen that made fast to the shogging-shaft I' is an arm i⁶, which carries a bowl i⁷, that is brought by the rocking of the shaft I' into the plane of motion of one or other of the acting surfaces of the shogging-cam I³ I⁴, and thus the results above mentioned are obtained. The shogging-cam is formed of two parts I³ I⁴, each part being provided with two steps. The first step on the part I³, by acting upon the bowl i⁷ of the arm i⁶, will shift the forked arm I of the shogging-shaft laterally, thereby disconnecting the clutch from the miter-wheel and stopping the further action of this gear. A friction-clip may be fitted to the cam-shaft A to insure that the shogging-shaft I' shall make its endwise movement before the cam-shaft when the first step of the part I³ of the shogging-cam acts on the bowl i⁷ of the arm i⁶. This endwise movement of the shogging-shaft I' brings an adjustable collar secured to that shaft up to a fixed portion of the framing, and its endwise motion is thus limited. The second step of the part I³ of the shogging-cam as it comes around will now shog the cam-shaft in the reverse direction and bring the fashioning-cams into action. The cam i⁸ will hold the bowl of the arm i⁶ opposite the part I³ of the shogging-cam until the two steps of the shogging-cam have passed. The bowl carried by the arm i⁶ will then fall toward the cam-shaft, and at the proper time will be acted upon in like manner by the two steps of the other part I⁴ of the shogging-cam and move back first the shogging-shaft I' and then the cam-shaft A, whereby the knitting-cams will be again brought into action and the miter-wheels will be caused to transmit motion to the thread-carriers, as before.

The above-described arrangement of knitting-machine is equally adapted to the production of finished seamless stockings, the tubular leg and foot being made by the method described with reference to the production of tubular fashioned fabrics.

For making the heel and toe the machine is fitted with sliding pressers and the work is knitted on one set of needles only, the number of needles pressed being gradually reduced and then increased again, by which means the heel and toe known as the "Niantic" heel and toe are produced.

The present invention is herein described with reference to a machine having vertical and horizontal needles; but it may be applied with equal facility to machines having two sets of needles at angles other than a right angle, and the herein-described movements of the vertical needles may be applied to either of the two sets used. The knocking-over bits may also be stationary, as in a bearded-nee-

dle-rib frame, the amount of motion given to the needles being modified accordingly.

The drawings illustrate a machine fitted with fashioning-points at one side of each division only; but both sides of each division may be so fitted.

Having now described the said invention, what is claimed is—

1. In a straight-bar bearded-needle knitting-machine fitted with two sets of needles arranged similarly to the needles in a rib-frame, the combination with said needles, of means whereby the thread for all the courses is laid on one set of needles, and the threads of the alternate courses are formed respectively into loops, the one on the one set of needles and the other on the other set, substantially as and for the purpose herein set forth.

2. In a straight-bar bearded-needle knitting-machine fitted with two sets of needles arranged similarly to the needles in a rib-frame, the combination with said needles of friction-driven reciprocating thread-carriers operated to always deliver the thread to one and the same set of needles, and means whereby the thread for all the courses is laid on one set of needles and the threads of the alternate courses are formed respectively into loops, the one on the one set of needles and the other on the other set, to produce tubular work, substantially as herein described.

3. In a straight-bar bearded-needle knitting-machine fitted with two sets of needles arranged similarly to the needles in a rib-frame, the combination with said needles, of friction-driven reciprocating thread-carriers, mechanism for fashioning at one end of the "division," and means whereby the thread for all the courses is laid on one set of needles and the threads of the alternate courses are formed respectively into loops, the one on the one set of needles and the other on the other set to produce tubular work, substantially as herein described.

4. In a bearded-needle knitting-machine with two sets of needles arranged similarly to the needles in a rib-frame, the combination with the said needles, of friction-driven reciprocating thread-carriers, mechanism for fashioning at one or both edges of a division of the fabric, movable knocking-over bits, mechanism operating the said knocking-over bits, and a cam-shaft fitted with cams, which, at each revolution, operates one set of needles, so that the thread laid thereon at one traverse of the thread-carrier, is automatically formed into loops on those needles, while the thread laid upon the same needles at the next succeeding traverse of the thread-carrier, is automatically indented on those needles, and transferred to the other set of needles, and formed into loops on such other set of needles, substantially as set forth.

5. In a bearded-needle knitting-machine with two sets of needles arranged similarly to the needles in a rib-frame, the combination

with the said needles, of friction-driven reciprocating thread-carriers, mechanisms for fashioning at one or both edges of a division of the fabric, and mechanism operating the 5 said needles, whereby the thread laid on one set of needles at two successive traverses of the thread-carrier, is automatically formed into two rows of loops on such needles, while the thread laid on the same needles as the 10 two succeeding traverses of the thread-carrier, is indented on such needles, and auto-

matically transferred to the other set of needles, for the formation of two rows of loops on such other needles, substantially as set forth.

CHARLES L. STURTEVANT,
Ancillary administrator of the estate of Samuel Lowe, deceased.
